UNITED STATES PATENT OFFICE.

THORNTON G. GRAHAM, OF KENT, OHIO, ASSIGNOR TO THE MASON TIRE & RUBBER COMPANY, OF KENT, OHIO, A CORPORATION OF OHIO.

DESIGN FOR A TREAD FOR PNEUMATIC TIRES.

Application filed January 23, 1923. Serial No. 4,971. Term of patent 14 years.

To all whom it may concern:

Be it known that I, THORNTON G. GRAHAM, citizen of the United States of America, residing at Kent, in the county of Portage and State of Ohio, have invented a certain new, original, and ornamental Design for Tread for Pneumatic Tires, of which the following is a specification, reference being had to the accompanying drawings, forming a part thereof, wherein—

Figure 1 is a perspective view of a section of the pneumatic tire showing my new design, wherein the tread exhibits a central circumferential member including spaced quadrilateral figures flanked by opposing

D-shaped members symmetrically disposed back to back, and

Fig. 2 is a composite transverse section thereof, the left hand portion of which is taken through a D-shaped member and the right hand portion through the adjacent quadrilateral figure better to illustrate the features of said design.

I claim:

The ornamental design for a tread for pneumatic tires, as shown and described.

In testimony whereof I do now affix my signature.

THORNTON G. GRAHAM.
